CLAIM

The ornamental design for a packaging container for a fingernail set, substantially as shown and described.

DESCRIPTION

FIG. 1 is a top perspective view of a packaging container for a fingernail set showing my new design;

FIG. 2 is a top plan view;

FIG. 3 is a bottom plan view;

FIG. 4 is a side elevational view;

FIG. 5 is an end elevational view;

FIG. 6 is an exploded top perspective view; and

FIG. 7 is an enlarged sectional view taken in the direction of the arrows 7—7 of FIG. 6.
